UNITED STATES PATENT OFFICE.

ELWIN H. ROONEY, OF WHITINSVILLE, MASSACHUSETTS.

CARDING-MACHINE.

1,249,833.

Specification of Letters Patent. Patented Dec. 11, 1917.

Application filed April 23, 1915. Serial No. 23,282.

To all whom it may concern:

Be it known that I, ELWIN H. ROONEY, a citizen of the United States, residing in Whitinsville, Massachusetts, have invented 5 the following described new and useful Improvements in Carding-Machines.

The object of this improvement in carding machines is to provide effective and practical means for removing the dirt which 10 collects in the card clothing of the card and doffer cylinders. The mechanism includes rollers which are moved into and out of engagement with the card-clothed cylinders, together with means for effecting such movement automatically and positively acting 15 means for automatically connecting and disconnecting the rollers and their driving means, whereby the rotation of the rollers is started and stopped at exactly determinable times in the cycle of operations and 20 the driving of the rollers is in one direction and during brief periods only, the result of this combination being to secure a high degree of efficiency and to avoid unnecessary 25 wear and complication. With the stripping rollers, which engage the cylinders, are associated clearing rollers, mounted on the same movable supports and connected to be driven at greater surface speed than the 30 strippers, in order to take the stripings therefrom. A receptacle for receiving the material from the clearing roller is also mounted on the support with each pair of 35 rollers, so as to be moved to and fro therewith. The device thus constituted is brought into engagement with the card cylinder or the doffer cylinder, as the case may be, at intervals, the rollers are driven while in the 40 said position and for a brief period after separation from the cylinder, to permit the rollers to clear themselves, and then become 45 stationary, in which condition they remain for a substantially longer period than that during which they were driven. Other features of the invention will be recognized by those skilled in the art as the specification proceeds.

In the accompanying drawings:

Figure 1 is a partial side elevation of a 50 carding machine, showing the invention applied thereto and omitting for the sake of clearness various familiar features of card construction which are not necessary to an understanding of this invention.

Fig. 2 is a side elevation, on an enlarged 55 scale, illustrating more particularly the mechanism for moving the rollers to and from the card-clothed cylinders;

Fig. 3 is a detail side elevation of one of 60 the lower roller-carrying arms;

Fig. 4 is a view in end elevation and partly in section of the general mechanism;

Fig. 5 is an enlarged cross-section through 65 the cam member;

Fig. 6 is a face view thereof;

Fig. 7 is an enlarged side elevation of the 70 upper roller support; and

Fig. 8 is a fragmentary elevation, partly 75 in section, looking at right angles to Fig. 7.

In these views 11 is the card cylinder and 12 the doffer cylinder, both provided with appropriate card clothing. The doffer cylinder is shown driven from the card cylinder shaft by a band 13, which passes around 80 pulleys on the shafts of the cylinders and about a binder pulley 14. Other details of known construction in carding machines are omitted as unnecessary to an understanding of the improvements.

The devices for removing the dirt from the card clothing of the cylinders comprise two sets of rollers 15 and 16 and 15^a and 16^a, one set being above and operative upon the doffer cylinder and the other below and 85 operative upon the card cylinder. These rollers are likewise covered with card clothing, and 15 and 15^a are the stripping rollers to engage with the cylinders, and 16 and 16^a the clearing rollers designed to take the 90 stripings from the stripping rollers.

Each pair of rollers is mounted for movement to and from its cylinder. The upper set is carried by a support comprising a pair of swinging arms 17 connected by a cross- 95 rod 18. Only one of the arms is shown in the drawings, it being understood that the arms at opposite sides of the machine are symmetrical duplicates. In like manner the lower set of rollers is journaled in a 100 swinging support comprising arms 17^a, of which only the arm at the near side of the machine is illustrated. At each side of the machine the arms 17 and 17^a are mounted on a common bearing or support consisting 105 of a fixed shaft 19 projecting from a bracket 20, which in turn is fastened to a suitable frame part 21.

The means for swinging the roller-carrying arms comprises a cam wheel 28 mounted on a shaft 23 and driven from a longitudinal countershaft 24 by a worm 25 on the 5 countershaft meshing with a worm wheel 26, which has compounded with it a pinion 27, (see dotted lines Fig. 1), the latter meshing with the cam-gear 28. By a gear train of this or other suitable character the cam is rotated at a low rate of speed appropriate to the purposes of the invention. There is 10 preferably one of these cam members at each side of the machine, but the driving train occurs only at one side since both 15 members are fixed to the same driven shaft 23.

As more particularly illustrated in Figs. 5 and 6, the said cam member is composed of an outer part 29 and an inner part 30, 20 formed, respectively, with cam grooves 31 and 32. The outer part is united with the hub 33, being integral in the present case, and the inner part is an annulus occupying the recess between this hub and the inner 25 wall of the groove 31. The two parts are held together by bolts 34, which occupy adjustment slots 35 in the part 30, permitting the cams to be angularly adjusted with reference to each other and to the proper timing of the parts. The outer cam groove (31) controls a roller stud 36 (Fig. 2) projecting into it from the lower end of the upper arm 17, and the inner groove (32) similarly receives a roller stud projection 36^a on the other arm 17^a, the connections of the roller-studs to their respective arms being slotted as indicated to permit of adjustment. The contour of the cam grooves is such that their major portions are concentric with the axis, the eccentric portions being relatively limited in extent. It results from this and from the slow movement of the cam that the rollers are held most of the time away from the card and doffer cylinders and are brought into engagement therewith for brief periods only and at comparatively long intervals.

The rollers are preferably driven from the card cylinder shaft through a belt 38, 50 which engages the sheave element 39 (Fig. 4) of a clutch mounted on the same shaft 19 which forms the pivot of the swinging arms. The other element 40 of said clutch is provided with large and small sheave or pulley 55 portions 41 and 42, of which 41 drives the lower rollers through a band 43, and 42 the upper rollers through a band 44. Band 44 is trained so that both its courses pass at the same sides of pulleys 45 and 46 (Fig. 4) 60 of which one is fast and one loose, on the journal extension 47 of the stripping roller 15, and around a single pulley 48 fast on the journal extension 49 of the clearing roller 16. Belt 43 coöperates in like manner with

fast and loose pulleys 45^a and 46^a on journal 65 extension 47^a and pulley 48^a on journal extension 49^a, of the lower rollers.

The clutch faces of the driving elements 39 and 40, formed as cones 50 in the present instance, are normally separated by a spring 70 51, but other forms of clutches are equally serviceable. The said clutch is controlled positively and automatically in accordance with the cam control of the swinging arms, thus insuring the rollers being set in motion 75 at the proper moments and the driving thereof being continued throughout the period for which it is desired they shall rotate. To this end the member 40 is mounted slidably on the shaft 19 and is shifted by 80 a lever 52, which latter is fulcrumed intermediate its ends on a pin 53 fixed adjustably in a slot 54 in a stationary arm 55 projecting from the bracket 20. The lower end of this lever carries a roller bearing 56, engaged at intervals by a cam 57 on the face of the cam disk 28, which automatically closes and opens the clutch, at predetermined intervals, the opening movement taking place by virtue of the spring 51. Manifestly, if desired, the spring could be dispensed with and the cam caused to operate the clutch lever positively in both directions. For purposes of adjustment the cam piece 57 is formed with a curved slot 58, 95 through which passes a screw 59 securing it to the cam member 29.

It will be observed that the ratios of the various elements of the driving means of the rollers are such that the lower rollers are 100 driven faster than the upper rollers, since the card cylinder revolves at a higher speed than the doffer; furthermore, the clearing roller of each pair is driven faster than the stripping roller and in the opposite direction. It will also be understood that each stripping roller is driven at greater surface speed than the card-clothed cylinder with which it engages, in order to take the dirt therefrom.

It will be further understood that the roller driving elements, the clutch, clutch lever and cam piece 57 need not be duplicated at both sides of the machine, since it is sufficient to drive the rollers by connections engaging them at one end.

The mounting of the rollers on the arms is illustrated more particularly in Figs. 7 and 8. The upper arms 17 have bearings 60 at their upper ends, through which pass the roller journals 47, and end plates 61, at opposite ends of the rollers, have each a hub portion 62 receiving the adjacent journal and entering the bearing in the arm. The plate is further connected with the arm 120 by a slotted portion 63, through which passes the rod 18 having the clamping nuts 64 and 65, by which the plate may be set at various

angular positions, thus adjusting the clearing roller about the stripping roller. The plate is also apertured to accommodate a bearing 66 for the journal of the clearing roller, and this bearing is made rectilinearly adjustable toward and from the stripping roller by slide engaging portions 67 normally clamped by a screw 68. The mounting of the lower rollers is similar. Both sets of 10 rollers are inclosed, except at the active side of the stripping rollers, by casings 69 and 69^a united to the end plates.

Receptacles 70 and 70^a are also mounted on the swinging supports, in positions to receive the stripings from the clearing rollers. These receptacles may be made of sheet metal to constitute extensions of the casings, extend the full length of the rollers, and can readily be connected with an exhaust for automatically withdrawing the dirt as deposited.

In Figs. 1 and 2 it will be observed that the various cam elements are so set as to be in action at the same time. According 25 to the preferred timing, the face cam 57 rides beneath the roller of the clutch lever 52 and throws in the clutch, so as to start the rollers revolving immediately before or just as the cam groove 32 causes the lower 30 arms 17^a to swing the stripping roller 15^a into engagement with the card cylinder. Next, and preferably before the said roller has left the card cylinder, the cam groove 31 brings the upper set of rollers into 35 operative relation to the doffer cylinder. The lower rollers are now returned to normal position and directly thereafter the upper rollers are restored. Manifestly, however, the two sets of rollers could be shifted simultaneously or in the reverse order, if preferred. Finally, the face cam rides out 40 from beneath the clutch lever and the rollers cease revolving, but the length of the face cam is such that this does not occur until 45 a short time has elapsed after the separation of the rollers from the cylinders, thus insuring the rollers making a sufficient number of revolutions after stripping ceases to enable the clearing rollers to complete the removal of the stripings from the stripper 50 rollers and to deposit the same in the receptacles. The cams 31 and 32 are so designed, as indicated, that the lower stripping roller is held against the card cylinder for 55 a longer period than that during which the upper stripper operates on the doffer cylinder. The uniting of the cam means for controlling the movable roller supports and also the driving means into a compound cam 60 device composed of relatively adjustable parts is desirable for the compactness of the construction and the facility which it affords in regulating the timing of the operations. The mounting of the clutch on the

same axis or bearing as the supports is likewise advantageous in economy of space and parts, and in addition obviates undesirable slackening or tightening of the bands connecting the driving element 40 with the rollers, when the supports are swung to and fro. Various other advantages of the particular preferred features of construction illustrated will be appreciated by those skilled in the art.

What is claimed as new is:

1. In a carding machine, a card-clothed cylinder, and automatic stripping mechanism comprising an intermittently rotating stripping roller, means for driving the same, means for automatically moving the roller 80 into and out of engagement with the cylinder, and positively acting means for automatically connecting and disconnecting the roller and its driving means, the mechanism being so organized and arranged that the 85 roller is driven for predetermined definite periods comprising the periods when in engagement with the cylinder, and is at other times disconnected from the drive.

2. In a carding machine having a card-clothed cylinder, a stripping roller mounted in supports whereby it may be moved to and from said cylinder, and automatic means for effecting such movement, in combination with means for driving the roller, and a 95 rotary driven cam member connected with an element of said driving means so as to start and stop the roller at predetermined times, the roller during brief periods rotating in engagement with the cylinder at 100 greater surface speed, and being at rest during major periods when separated from the cylinder, the driving of the roller being entirely in one direction.

3. In a carding machine and in combination with a card-clothed cylinder, a stripping roller, a movable support for carrying the same to and from the cylinder, means for driving the roller, said driving means including disconnectible elements, and 110 united relatively adjustable cam elements controlling respectively the movable roller support and said disconnectible drive elements.

4. In a carding machine and in combination with a card-clothed cylinder, a stripping roller, a swinging support for carrying the same to and from the cylinder, a driving connection for the stripping roller unaffected by the movement of said support, 120 a clutch connected with said driving connection, and a rotary member bearing cams controlling respectively the movable roller support and said clutch.

5. In a carding machine and in combination with a card-clothed cylinder, a stripping roller, a movable support for carrying the same to and from the cylinder, a

- driving connection for the stripping roller unaffected by the movement of said support, a clutch connected with said driving connection, and a rotary member bearing an eccentric cam and a face cam controlling one the movable roller support and the other said clutch. 65
- 5 6. In a carding machine comprising a card-clothed cylinder, a stripping roller, a clearing roller, a support on which both rollers are mounted, said support being movable to bring the stripping roller into and out of engagement with the cylinder, means for driving said rollers in directions opposite to each other and at different surface speeds, automatic means for moving the roller support, and means for starting and stopping the rollers in accordance with the operation of the last-mentioned means. 70
- 10 7. In a carding machine having a card-clothed cylinder, a stripping roller, a clearing roller, a receptacle to receive the stripings from the clearing roller, a support for both rollers and the receptacle, said support being movable to bring the stripping roller into and out of engagement with the cylinder, means for driving the rollers, and automatic mechanism for moving said support and for connecting and disconnecting the drive of the rollers. 75
- 15 8. In a carding machine having a card-clothed cylinder, a stripping roller, a clearing roller, means for shifting both of the rollers to bring the stripping roller into and out of engagement with the cylinder, the rollers remaining in engagement with each other, and means for driving the rollers while stripping and clearing, the rollers being at other times stationary. 80
- 20 9. In a carding machine having a card-clothed cylinder, a stripping roller, a clearing roller, a movable support for both said rollers whereby the stripping roller is moved into and out of engagement with the cylinder, mechanism for operating said support, and means for driving the rollers in directions opposite to each other and at different surface speeds while stripping and clearing, the rollers being at other times stationary. 85
- 25 10. In a carding machine having a card-clothed cylinder, a stripping roller, a clearing roller, means for automatically shifting both rollers to bring the stripping roller into engagement with the cylinder for short periods and to separate the same from the cylinder for relatively long periods, means for driving the rollers, and positively acting means for automatically connecting and disconnecting the rollers and their driving means, the rollers being driven while in cylinder-engaging position and for a brief period thereafter and at other times being stationary. 90
- 30 11. In a carding machine having a card-clothed cylinder, a stripping roller, a swinging arm supporting the same for movement into and out of engagement with the cylinder, a bearing on which said arm is mounted, and clutch elements also mounted on said bearing and connected respectively with the roller and with suitable driving means, in combination with means for automatically operating said arm and connecting and disconnecting said clutch elements. 95
- 35 12. In a carding machine, the combination with the card and doffer cylinders, of stripping rollers adapted to engage, respectively, the card cylinder and the doffer cylinder, swinging arms supporting said rollers for movement to and from the card and doffer cylinders, respectively, a common bearing on which said arms are mounted, and means for driving the rollers and actuating the arms. 100
- 40 13. In a carding machine, the combination with the card and doffer cylinders, of a stripping roller below the card cylinder for engagement therewith, another stripping roller above the doffer cylinder for engagement with the same, a bearing, supporting arms on said bearing extending downward and upward respectively to carry said rollers, separable driving elements on said bearing, connections between the driven one of said elements and both rollers, and automatic mechanism controlling the arms and said separable driving elements. 105
- 45 14. In a carding machine, the combination with the card and doffer cylinders, of stripping rollers adapted to engage, respectively, the card cylinder and the doffer cylinder, swinging arms supporting said rollers for movement to and from the card and doffer cylinders, a clutch, driving connections between the driven element of the clutch and the stripping rollers of both cylinders, and automatic mechanism controlling the arms and the clutch. 110
- 50 15. In a carding machine, the combination with the card and doffer cylinders, of stripping rollers adapted to engage, respectively, the card cylinder and the doffer cylinder, swinging arms supporting said rollers for movement to and from their cylinders, means for driving the rollers, and a cam member having cam grooves controlling said arms and a face portion controlling an element of said driving means to start and stop the rollers. 115
- 55 16. In a carding machine having a card clothed cylinder, a stripping roller, a pivotally mounted arm supporting said roller for movement to and from the cylinder, means for automatically actuating said arm, and a drive wheel journaled at the pivotal axis of the arm and connected with the roller for revolving the same. 120
- 60 17. In a carding machine having a card-

clothed cylinder, a stripping roller, a swinging arm supporting said roller for movement to and from the cylinder, means for automatically actuating said arm, a bearing about which said arm swings, and an element for the driving of the roller journaled on said bearing.

18. In a carding machine having a card-clothed cylinder, a stripping roller, a swinging arm supporting said roller for movement to and from the cylinder, means for driving the roller including an element journaled coaxially with the arm, and means for automatically controlling the arm and starting and stopping the roller.

19. In a carding machine having a card-clothed cylinder, a stripping roller, a swinging support for said roller, a housing mounted rotatably upon the axis of the stripping roller, means for fixing said housing upon the swinging support, and a clearing roller carried by the housing.

20. In a carding machine having a card-clothed cylinder, a stripping roller, a swinging support receiving the journals of said roller, end plates carried by the swinging support and rotatable co-axially with said journals and provided with means for fixing them to said swing support, and a hood and a clearing roller carried by said plates.

21. In a carding machine having a card-clothed cylinder, a stripping roller, a swinging support receiving the journals of said roller, a hood carried by the end plates, plates adjustable co-axially with said journals and provided with means for fixing them to said swinging support, bearings adjustable on said plates toward and from the stripping roller, and a clearing roller journaled in said bearings.

22. In a carding machine, the combination with a card cylinder and a doffer cylinder, a stripping device arranged to coöperate with the card cylinder and a stripping device arranged to coöperate with the doffer cylinder, of separate movable supports for said stripping devices whereby they may be shifted into and out of engagement with the respective cylinders, means for driving the rollers, and a compound cam member having relatively adjustable eccentric elements for operating said supports and in addition thereto an adjustable element for controlling said driving means.

In testimony whereof, I have signed this specification in the presence of two witnesses.

ELWIN H. ROONEY.
